BASSINET LINER

Jesse Lynch Meredith, Jr., and Barbara B
Meredith, Alameda, Calif.

Application March 6, 1950, Serial No. 147,928

2 Claims. (Cl. 219—46)

1

This invention relates to liners for children's beds such as bassinets and particularly to liners of this type which are heated.

The conventional bassinet consists of an open-topped receptacle such as a basket which is provided with a mattress upon which a child may lie. The child is covered by blankets and the inside of the conventional bassinet is usually lined to prevent drafts, etc.

Bassinets thus constructed are unsatisfactory for a variety of reasons including, by way of example, their failure to provide means for keeping the child warm when the child throws off its covers.

It is an object of this invention to provide a device of this character in which heating elements are incorporated in the side walls of the device to warm the child.

It is a further object of this invention to provide a device of this character which will provide sufficient circulation to prevent overheating of the child, yet which will not reduce the effect of the heated walls.

Other objects and advantages of this invention will appear from the following specification taken in conjunction with the accompanying drawing in which:

Figure 1 represents a side view, in cross-section, of a bassinet incorporating our invention;

Figure 2 is a view taken along the line 2—2 of Figure 1 of the head of the bassinet;

Figure 3 is a view taken along the line 3—3 of Figure 1 of the foot of the bassinet;

Figure 4 is a top plan view of the bassinet incorporating our invention;

Figure 5 is an enlarged cross-sectional view taken along the line 5—5 of Figure 1; and

Figure 6 is a diagrammatic illustration of the typical temperature range maintained within a bassinet utilizing our invention.

As illustrated in the drawing, a bassinet 10 of suitable size and shape is provided which consists of side walls 11 and a bottom wall 12 and which is open at the top 13. For purposes of designation herein, the foot of the bassinet will be termed "end 14" and the head of the bassinet will be termed "end 16".

The bassinet 10 is provided with a liner 17 which, as illustrated more particularly in Figure 5, is composed of an inner wall member 18 and an outer member 19, between which members there is provided a suitable resistance heating element 21 which, as illustrated in Figure 1, is adapted to be connected to a source of electric current, not shown. A thermostatic switch means

2

23 is provided which, in the modification herein illustrated, is responsive to the temperature of the room within which the bassinet 10 is placed. The liner 17 is adapted to lie against the inside 5 of the walls 11 of the bassinet, with the outer member 19 in engagement with the wall 11 of the bassinet 10.

As illustrated in Figures 1, 2, 3 and 4, the resistance element 21 is positioned in the liner 17 10 in a particular manner. It will be noted, for example, that at the foot end, or end 14, of the bassinet 10, the resistance element 21 is placed in a single run along the extreme lower edge of the liner 17 and, because of the fact that there 15 is but a single run of the same, there will be a minimum of heat delivered therefrom. However, along the sides 11 of the bassinet 10 the resistance element 21 is laid in a number of convolutions 21a extending from a point at about the upper 20 level of a mattress 24 to a point about half way up the sides of the bassinet 10. Near the head end, or end 16, of the bassinet 10, the resistance element 21 is brought upwardly to a point adjacent the upper edge of the wall 11 to form 25 a number of convolutions 21b, as illustrated in Figures 1 and 2. The resistance element 21 is then brought down and the liner of the bassinet along the side 11b is provided with substantially the same number of convolutions in the same zone as has previously been described in connection with the side 11a.

It will be obvious that when electric current is introduced into the resistance element 21, heat will be discharged into the bassinet whereby an 30 infant, for example, lying therewithin will be kept warm.

A partial cover 26 is provided to enclose a certain portion of the otherwise open top 13 of the bassinet. Cover 26 provides opening 27 near 35 the foot of the bassinet and opening 28 near the head thereof. The area of the opening 27 is approximately 8% of the area of the entire opening 13 while the opening 28 is approximately 42% of the entire opening 13. The area of the cover 40 26 is approximately one-half of the entire opening 13.

We have found that the outer wall 19 of the liner 17 is preferably made of woolen material whereas the inner wall 18 is preferably formed 45 of cotton or flannel. The outer wall 19, being of wool, will tend to retain the heat discharged from the element 21 and reflect the same inwardly. Since the inner wall 18 is composed of cotton or flannel, the heat will pass therethrough 50 quite easily.

Operation of the apparatus may briefly be described as follows: The lining 17 is placed within the bassinet 10 substantially as illustrated in the drawings and the resistance element 21 is connected, through thermostat 23 to a suitable source of electric current. The thermostat is set for the degree of heat required or desired within the bassinet 10. The resistance element 21 is heated and the heat is reflected inwardly toward the inside of the bassinet 10 by the wall 19 of the liner 17. The resistance element 21 will tend to heat the air within the bassinet. Because of the heat generated by the convolutions near the head 16 of the bassinet 10, the air immediately adjacent the same will tend to rise. The rising of this air and the discharge of the same through the opening 28 will tend to draw cool air into the opening 27. Since there is little or no heat generated adjacent the opening 27, the inflow of air therethrough will not be interrupted by the exhaust of warm air therefrom. The introduction of air through the opening 27 and the exhaust of air through the opening 28 will maintain slight but sufficient circulation through the entire apparatus. Warmth will be imparted from the side walls inwardly toward the center of the bassinet.

We have found that an infant placed in such a bassinet with the thermostat set, for example, at 70° F. may be placed in the bassinet with no further covering and yet remain warm. The circulation of air through the bassinet provided by the proper placement of the resistance element 21 near the periphery of the opening 28, and the elimination of the heating element at the opening 27, will prevent the atmosphere within the bassinet from becoming "close" and will prevent overheating of the occupant of the bassinet.

We have found, specifically, and by way of example, that a bassinet constructed substantially as illustrated in the drawings will provide the temperatures as indicated in Figure 6, where the air entering the device is of approximately 74° F. and is elevated to approximately a temperature of 79° F. about midway through its path. The air will be exhausted through the opening 28 and, 45 ultimately recirculated through the opening 27.

We claim:

1. A bassinet liner comprising a pair of walls of flexible blanket material having a heating element therebetween, said element being only along the lower edge of the side walls and only along the upper edge of one end of the liner, said end forming a juncture between said walls, and a cover adapted to extend from the upper edge of one side wall to the upper edge of the other side wall and providing a pair of openings of unequal size in the top of a bassinet, the larger opening being adjacent that end of the liner in which the heating element is along the upper edge.

2. A bassinet construction comprising an outer wall of flexible blanket material, an inner wall of flexible blanket material, and a heating element between said walls, said element being formed in convolutions only along the lower portion of the side walls of said liner and in convolutions only along the upper portion of an end of said liner, and a partial cover extending from the top of one side wall to the top of the other side wall forming a pair of openings of unequal size in the top portion of a bassinet, the larger opening being adjacent that end of the liner in which the convolutions of the heating element are along the upper portion of the liner.
